UNITED STATES PATENT OFFICE

WILLIAM H. DAYTON, OF TORRINGTON, CONNECTICUT, ASSIGNOR TO THE EXCELSIOR NEEDLE COMPANY, OF SAME PLACE.

MACHINE FOR POLISHING NEEDLE-POINTS.

SPECIFICATION forming part of Letters Patent No. 449,313, dated March 31, 1891.

Application filed July 25, 1890. Serial No. 359,917. (No model.)

To all whom it may concern:

Be it known that I, WILLIAM H. DAYTON, a citizen of the United States, residing at Torrington, in the county of Litchfield and State 5 of Connecticut, have invented an Improvement in Machines for Polishing Needle-Points, of which the following is a specification.

Sewing-machine needles are usually manufactured with a shank that is of larger diameter than the needle itself, and after the needles have been reduced to the proper size from the wire that corresponds in diameter to the shank the blank is cut off at the proper length and the point sharpened by grinding, 10 and during this grinding operation the point is sometimes made as a straight taper, and in other instances the point is ground more or less elliptical in section, and in order to more perfectly adapt the point of the needle to the uses to which it is to be put such point is 15 polished by the action of a fine emery-band, such band being drawn from the body of the needle toward and away from the point in order to polish the metal toward the point itself. 20 The present improvements are for performing the polishing operation last above mentioned, and in this machine the polishing-belt is adapted to being adjusted in its position so as to polish the entire point of the 25 needle without injury or varying materially the shape previously given to the point in the grinding operation, and this machine, while primarily intended for the polishing of needle-points, might also be used for grinding 30 said points if the emery-belt was made with emery of the proper quality for performing the grinding operation.

In the drawings, Figure 1 is a plan view of the machine. Fig. 2 is a vertical section near 40 the line $x-x$ of Fig. 1. Fig. 3 is a partial elevation of the machine at one side thereof. Fig. 4 represents the gearing for connecting the feeding-screws. Fig. 5 is a partial plan, in larger size, of the feeding-screws at the entrance end, and Fig. 6 is a section representing the feeding-screws and a needle-blank in 45 position upon them.

The bed of the machine is of suitable size and shape, usually rectangular, as shown at 50 A, and upon this bed are slideways 2, supporting the base B, that carries the journal

box or bearing 3, through which passes the shaft C, having upon it a driving-pulley D, and one end of said shaft C projects and is provided with a pulley E for the emery-belt 55 F, and there is a screw 4, passing through a lug upon the base B and into the bed A, for moving such base B and the bearings 3 and shaft C for tightening the emery-belt F, as required from time to time. The emery-belt 60 F passes around a small roller G, which comes above the needle-blank i, which needle-blank is presented to the action of the emery-belt in a manner hereinafter described, and there is a second roller H, which bears upon the 65 emery-belt F, and according to the relative positions of these rollers G and H, so the emery-belt F where it passes from one roller to the other will be at a greater or less angle to the needle-blank i to adapt the belt to the 70 shape of the point, and upon reference to Fig. 2 it will be seen that the point of the needle is exposed to the action of this emery-belt F between the rollers G and H.

There is a compound lever K for carrying 75 the rollers G and H, and this lever K is pivoted at 5 upon the stand K', that is adjustably connected to the bed A by the clamping-screw 6, and this compound lever K is made in two parts, the portion 7 being in the 80 form of an arm extending out from the pivot 5, and the portion 8 forms the second joint of the arm, and it is pivoted at 9, so that the second joint of the arm can be swung upon the pivot 9 into any desired position in relation to the first joint 7 of the arm, and there is a wheel I, rigidly fixed to the outer end of the pivot-pin 9, and there are lugs 10 on the arm 8, with a screw-pinion 11 between such lugs and in gear with the wheel I, so that by 90 rotating this screw-pinion 11 by a suitable key or wrench the angle of the second joint 8 of the compound lever to the first joint 7 of said lever can be changed, and in so doing the positions of the rollers G and H to the 95 pivot 5 will be varied and the axes of said rollers brought more nearly into a plane passing through the pivot 5 or at a greater angle to such plane, thereby varying the angle of that portion of the emery-belt F which bears 100 against the points of the needles, and I make use of an adjusting-screw 12, passing through

a lug upon the arm 8 and resting upon the bed A or upon a stud rising from said bed, so as to raise or lower the outer end of the compound lever K and regulate the pressure 5 of the emery-belt upon the needle-points. It will be understood that by the screw 4 the emery-belt can be tightened or slackened by moving the base B, and when access is required to the needle-blanks the compound lever 10 K can be swung up and with it the rollers G and H and emery-belt F, and in so doing the belt E is slackened, and it can be raised, as aforesaid, without necessarily stopping the rotation of the shaft C, and the belt 15 can be taken off and another one substituted whenever necessary.

In machines for polishing needles there has been a stationary rest, upon which the shanks or needles lie during the polishing or grinding operation, and also a belt moving above such needles and pressed into contact therewith, so as to rotate the needles upon the rest as such needles are rolled along by the belt. Devices of this character are used in my machine. The rest L for the needle-blank is formed as a rail or ledge resting upon the bed A, and the endless belt N is directly over the rest, the needle-blanks *i* being between the belt and the rest, and the endless belt N 20 passes around wheels O O', the shafts of which are supported by the stocks P, said stocks having base-pieces resting upon the edge of the bed A and attached thereto by screws 13, passing through the slots in the 25 bases of the stocks and into the bed, and there is a horizontal screw 14, acting in one of the adjustable stocks for moving the same horizontally and tightening the belt N.

The endless belt N and the belt-wheels O O' 30 require to be moved with great regularity, so as to roll the needle-blanks along upon the rest L. With this object in view I make use of wheels M upon the arbors 15 of the belt-wheels O O', and these wheels M are acted 35 upon by screw-pinions Q upon the horizontal shaft R, that passes through the adjustable stocks P, and the shaft R is rotated by a band-pulley S'. These wheels M and screw-pinions Q are within boxes or housings upon the 40 adjustable stocks P, and there is a removable cap P' to each of the boxes or housings upon the adjustable stocks to give access to the respective parts for oiling. These housings prevent dust adhering to the wheels and 45 screw-pinions. The endless belt N passes beneath a trough-shaped strip of metal s, and there are springs t fastened upon a bar u and bearing upon the trough s with the force requisite for pressing the belt N upon the 50 shanks of the needle-blank *i* as such blanks are rolled along upon the ledge or rest L by the movement of the belt N and screws.

In machines of this general character two screws have been made use of for moving the 55 needle-blanks along progressively and with regularity. I make use of two screws for

the same purpose and combine with them the feeding device hereinafter described. The screw T receives into its groove the back ends of the needle-blank shanks, and the bodies of the screws rest in the groove of the feed-screw U, and it is preferable to make these screws right and left handed, as shown, and to rotate the screw U in the direction indicated by the arrows, so as to force the back 70 ends of the needle-blanks into the screw-threads of the screw T, and to rotate this screw T in the direction indicated, so that the friction may tend to press the needle-blanks down upon the rest L rather than to 75 lift them, and the driving-pulley 16 is usually placed upon the end of the screw T, and there are small driving-wheels or pinions 17, 18, 19, 20 for connecting the screw U to the screw T, and the pinions 19 and 20 are upon studs or 80 gudgeons projecting from an adjustable plate R', as seen in Fig. 4, upon the back edge of 85 the bed A.

At the supply end of the machine there is a small table V, upon which the needle-blanks 90 are laid, and there is a supply-screw W parallel with the screws T and U and in line with the rest L, and the bottoms of the screw-threads are upon the level, or nearly so, of the feed-table V and the top of the rest L, and 95 this supply-screw W is driven by the gears 21 and 22 from the screw T, and this supply-screw W is made with a screw-thread varying in its pitch—that is to say, the outer portion of such supply-screw W has about ten threads 100 to the inch, and the inner portion adjacent to the end of the rest L has about eight threads to the inch, or it has the same number of threads to the inch that there are in the screws T and U, the object of this construction being to allow the workmen to fill the screw-threads of the supply-screw W with the needle-blanks, the back ends of the needle-blanks resting against the gage of fence 23, and this screw W, running in unison with the screws 105 T and U, passes the needle-blanks along progressively and regularly, so that they are in the proper position and are received by the grooves of the respective screws T and U, and such needle-blanks pass along out of the supply-screw W and upon the rest L with precision; but the needle-blanks can be laid almost closely together in the portions of the supply-screw W that are contiguous to the 110 table V. Hence the attendant can discern 115 reliably that such supply-screw W is kept full of needle-blanks and the proper supply thereby insured. It will now be understood that as the needles are passed along through the machine by the combined operations of the 120 feeding-screws T and U they are simultaneously rotated by the endless belt N, rolling such needle-blanks upon the rest L, and during this operation the points are polished by 125 coming into contact with the revolving emery-belt F, and the needle is delivered in any 130 suitable manner. Usually it runs off the end

of the rest L, so as to fall shank downwardly through an opening in the bed and into a conveying-spout.

In some instances I make use of a rotary wiper or brush 25, which may be made of soft leather, upon a shaft 26, supported by a head 27, that can be raised or lowered by the screw 28, and this brush or wiper removes from the points of the needles any metallic particles which may adhere to the surface; but this brush or wiper may be dispensed with.

I claim as my invention—

1. The combination, with the emery-belt and the driving-pulley E for the same, of the two rolls G and H, around which the belt passes, the compound lever K, pivoted at 5 and supporting the rolls G and H, means for adjusting the angle of the second joint or 10 arm of the lever to the first, and means, substantially as specified, for supporting and rotating the needle-blanks while being acted upon by the emery-belt, substantially as set forth.
2. The compound lever K, having arms 7 and 8, in combination with the wheel I upon the joint 9, the screw-pinion 11 and its supporting-lugs for varying the position of the 15 second joint to the first arm of the compound lever, the emery-belt F, the driving-pulley D,

and the rolls G and H upon the compound lever, substantially as set forth.

3. The combination, with the emery-belt, the driving-pulley, the compound lever, and the belt-rolls supported by the same, of the 35 endless belt N, belt-wheel, adjustable stocks, driving-shaft, and screw-pinions and wheels for giving motion to the endless belt, substantially as set forth.

4. The combination, with the feed-screws T 40 and U, of the table V, a supply-screw W, and the rest L for the needles at the end of the supply-screw, substantially as and for the purposes set forth.

5. The combination, with the feed-screws T 45 and U, the table V, and supply-screw W, of the rest L for the needles at the end of the supply-screw W, the endless belt N above the rest for the needle-blanks, the wheels and mechanism for driving the endless belt, a 50 trough and springs for pressing the endless belt upon the needle-blanks, and an emery-belt and its driving pulley and rolls for acting upon the points of the needle-blanks, substantially as set forth.

Signed by me this 17th day of July, 1890.

WILLIAM H. DAYTON.
